A. S. HOFFMAN

FLUSHING VALVE

Filed Oct. 1, 1923

UNITED STATES PATENT OFFICE.

ALBERT S. HOFFMAN, OF CHICAGO, ILLINOIS.

FLUSHING VALVE.

Application filed October 1, 1923. Serial No. 665,903.

To all whom it may concern:

Be it known that I, ALBERT S. HOFFMAN, a citizen of the United States, residing at Chicago, in the county of Cook and State of Illinois, have invented a new and useful Improvement in Flushing Valves, of which the following is a specification.

My invention relates to a flushing valve for flushing water closets and similar purposes

- 10 and consists essentially of an enclosed casing having inlet and outlet openings, float mechanism for timing the duration of a flushing operation, and operating devices for moving the float mechanism and main valve
- 15 of the device to open position to begin the flushing operation. My construction is characterized by the use of relatively few parts and by the omission of diaphragms and all close fits as a result of which the de-
- 20 vice is reliable in operation and requires little attention after it is installed. The float mechanism employed is novel in that it is provided with means for permitting the water to gradually enter the float during a
- 25 flushing operation, through relatively large passageways until the floating effect is neutralized, at which time the float and attached valve constituting a unitary structure, descend under the action of gravity
- 30 to move the valve to its seat, thus terminating the flushing operation. The rate of flow of water into the float is determined by a passageway of reduced cross section communicating with the interior of the float,
- 35 which passageway of reduced cross section is however so disposed that water does not flow through it at any time, said passageway being for air only, to permit the air in the float to flow therewith when water is
- 40 flowing into the float and to permit air to flow into the float when the float is being drained, the rate of flow of the air into and from the float being determined by the cross section of the said air passageway.

- 45 A further feature of improvement of my construction consists of the assembly of all of the parts of the valve operating and controlling mechanism in such a manner that by removing the cover of the casing, all of the
- 50 movable parts may be removed as a single assembly unit having no loose parts that can be removed from the assembly unit without taking it apart, which if necessary may readily be done when said assembly unit is removed from the casing.
- 55 The above and other objects of my inven-

tion will best appear in connection with the drawings illustrating a preferred embodiment thereof, in which—

Fig. 1 shows the complete valve mechanism in vertical central sectional view, and

Fig. 2 is a sectional view of the parts shown in Fig. 1 taken along the line 2—2.

Similar numerals refer to similar parts throughout the several views.

As shown in Fig. 1 the flushing valve consists of a casing 10 of circular cross section having a pipe connection 11 for admitting water under pressure into the casing and a pipe connection 12 for delivering water 70 from the casing to effect the flushing operation. It will be noted that the supply connection 11 is horizontally disposed and the outlet connection 12 is vertically disposed to facilitate connecting the flushing valve in 75 any ordinary flushing system, but it will be understood that I do not limit myself to this particular arrangement and disposition of the inlet and outlet water connections.

At the upper end of the outlet connection 80 12 an integral flange 13 extends horizontally and partly across the upper end of the outlet connection from the body portion of the casing 10, which flange is provided with a central aperture 14 of substantially the same 85 diameter as the inner diameter of a valve seat 15 supported on the flat upper horizontal surface of the flange 13. The seat 15 is in the form of a flat ring and may be of any suitable material to withstand the 90 action of water that will yield sufficiently under the action of the valve to interrupt the flow of water through the seat. The casing 10 carries an upwardly extending flange 16 around the outer edge of the seat 95 15 to maintain said seat in centered relation on its supporting flange 13.

The casing 10 is extended a short distance above the inlet connection 11 and is internally threaded as indicated at 10^a to receive 100 the external threads formed on a cup shaped member 17 constituting the lower portion of the float compartment. The bottom wall of the member 17 as indicated at 17^b, is inclined downwards somewhat towards the axis of 105 the casing and is provided in its upper surface with a recess 17^c of similar inclination. The recess 17^c loosely contains a dished washer 18 of an external diameter sufficiently smaller than the outer diameter of the recess 17^c, so that the washer will at all times 110 rest in the recess and so that it cannot rest

on the upper portion of the bottom 17^a of the member 17. The washer 18 is provided with a central opening somewhat larger than the diameter of a part of the float mechanism passing therethrough for a purpose to be described, and the washer 18 has substantially the same inclination downwardly towards the axis of the casing 10 as above described for the bottom 17^a of the member 17. The outer wall of the member 17 has formed therein two opposite apertures 19, 19^a, of sufficient size to permit water to flow freely therethrough, and with the exception of these apertures, the member 17 and washer 18 together constitute an imperforate enclosure for the lower portion of the float compartment, the only outlet being through the opening at the central portion of the washer 18. The bottom wall 17^a of the member 17 is provided with an opening 17^c slightly larger than the diameter of the valve to be described, and this opening is extended downwardly a sufficient distance to form a receptacle for the valve of the device, under the washer 18, when the valve is in its uppermost position during the flushing operation, as will be described. From the lower edge of the inner portion of the bottom 17^a, four arms 20 extend downwardly, the relation of these arms being more clearly shown in Fig. 2, and these arms at their lower ends carry a ring 21 tightly engaging the outer edge of the valve seat 15 when the member 17 is screwed down tightly in the threads 10^a, and thus the valve seat 15 is positively held in place against the action of the valve during its operation.

The flow of water through the valve seat 15 is controlled by a valve member or disc 22 having an annular bead 22^a of rounded conformation extending downwardly from its outer edge to engage the upper surface of the valve seat 15. From the inner portion of the bead 22^a the valve disc is tapered downwardly as indicated at 22^b towards the axis of the device, this tapered portion being of generally conical conformation and extending with the valve in its closed position, to substantially the lower plane of the valve seat 15. From the lower end of the tapered portion 22^b, the valve structure is continued downwardly in the form of a stem 23 disposed axially in the outlet connection 12. The lower end of the stem 23 is bored axially as indicated at 23^a and of a diameter to permit air to freely flow through said bore, and the upper portion of the stem is similarly bored as indicated at 23^b to receive the lower end of an air tube 24 which is preferably a pressed fit in said bore 23^b. The bores 23^a and 23^b are connected by an intermediate bore 23^c of substantially the internal diameter of the tube 24 and thus a continuous air passage is provided from the lower end of the stem 23 to

the upper end of the tube 24. Immediately below the valve disc 22 four holes 25 are formed which extend inwardly from the inclined surface 22^b into a bore 26 formed in an extension 27 projecting upwardly from the valve disc 22, said bore 26 being of sufficient diameter to allow ample clearance around the tube 24 for the flow of water through said bore 26 to and through the holes 25. The holes 25 are inclined downwardly and outwardly to drain the bore 26 when the valve is in its seated position and said holes are preferably equally spaced.

The opening 17^c is preferably hexagonal or of other flat sided shape for facilitating 30 tightly screwing the member 17 into the threads 10^a by means of a correspondingly shaped tool.

The extension 27 is externally threaded to engage corresponding threads formed on a 35 downwardly projecting sleeve 28 extending centrally from the bottom wall 29 of the float 30, the bottom wall being inclined downwardly towards the axis of the device to facilitate draining water from the float 40 during the closed condition of the valve. The external diameter of the extension 28 is slightly smaller than the opening through the washer 18 to prevent friction and binding of the parts. The float 30 consists of 45 an inverted cup shape member having integral top and side walls, the side wall being of substantially circular cross section and threaded at its lower end to tightly engage 50 corresponding threads formed on the outer 100 edge of the bottom wall 29 as a result of which the member 30 and the bottom wall 29 together form a float which is wholly enclosed with the exception of the central bottom bore 26 and the holes 25 leading 105 therefrom. The tube 24 extends upwardly in the float and centrally thereof and terminates at a point sufficiently below the top wall of the float so that its upper end is always above the highest level that 110 water may reach in the float during its operation. The upper end of the tube 24 is preferably flattened as indicated at 24^a to provide a passageway of reduced cross section that will permit the air to enter and 115 leave the float at the desired rate.

To facilitate handling the float in placing it in the casing and removing it therefrom, the upper wall of the float is centrally indented as shown at 30^a and the indentation contains a lug 30^b that may be readily engaged to lift the float assembly from the casing.

The upper edge of the member 17 is extended above the upper edge of the casing 125 10 and is threaded on its outer surface to be engaged by corresponding internal threads on the lower portion of a cap 31 employed to enclose the float mechanism, and a gasket 32 is disposed between the lower edge of the 130

cap 31 and the upper edge of the casing 10 to tightly seal the joint between the cap and casing when the cap is screwed tightly against the gasket.

- 5 From the construction described it will appear that the valve member 22 and the float 30 are rigidly connected with each other by screwing the parts of the mechanism together in the manner described and 10 further that the washer 18, which loosely rests in the recess 17^c and which is put in place on the float mechanism during its assembly, may readily be removed with the float mechanism, and that since the outer 15 diameter of the valve member 22 is slightly less than the diameter of the opening 17^c, when the cap 31 is removed, all of the float and valve mechanism may readily be lifted from the casing as a unitary structure, without disturbing any of the remaining parts. 20 This facilitates the ready assembly of the device and its ready inspection in the event it is necessary to clean or repair it at any time.
- 25 The outlet connection 12 is provided with a lateral extension 12^a which is externally threaded to be engaged by corresponding internal threads on the end of a sleeve 42 containing the operating mechanism. The 30 extension 12^a is counterbored as indicated to contain a gasket 33 held in place by a sleeve 34 which in turn is counterbored to receive one end of a spring 35. The sleeve 34 and the side wall of the connection 12 are 35 provided with a bore of the same diameter as the internal diameter of the gasket 33, to permit the passage therethrough of an operating rod 36 which is preferably of circular cross section and provided at its outer 40 end with a disc 36^a engaged on one side by the outer end of the spring 35 and on the outer side by the spherical end 37^a of an operating member 37. The spherical portion 37^a of the operating member is substantially circular and disc shaped and is held in place by the inwardly projecting flange 42^a of the sleeve 42. The operating member 37 carries an outwardly projecting handle 38 by which the operating member 45 may be tilted in any desired direction against the action of the spring 35, so that for any such tilting motion the rod 36 will be pushed inwardly into the connection 12. The inner end of the rod 36 extends substantially to the axis of the outlet connection 12 and is obliquely cut as indicated at 50 36^b, to provide a flat inclined wedge-like operating surface for engaging the lower end of the stem 23 when the rod 36 is moved 55 into the connection 12 by actuation of the handle 38. The lower end of the stem 23 is rounded as indicated adjacent the inclined operating surface 36^b and is separated therefrom a sufficient distance to permit wear of 60 the valve seat 15 without bringing the stem 65
- 23 and rod 36 into engagement with each other when the rod is in its outermost position. The rounded lower end of the stem 23 to be engaged by the operating surface 36^b, is preferably of cylindrical conformation to effect line contact between the stem and rod when the valve is operated, thus reducing wear of these parts to a minimum. The stem 23 is provided with two downwardly extending lugs 39, from opposite sides of the said stem so that one of said lugs lies upon each side of the end of the rod 36, which lugs are separated from said rod a sufficient amount to provide a working clearance between these parts, but one of said lugs 39 being shown in the drawings on account of the stem 23 being shown in vertical sectional view. The purpose of the lugs 39 is to prevent turning of the valve and float mechanism in the casing 10, thus maintaining the desired relation between the inclined surface 36^b and the cylindrical operating surface on the lower end of the stem 23. The relation between said stem and rod 70 also prevents the rod from turning away from its operative position.
- 75 It will be noted that the stem 23 carries a lug 23^a in the bore of the flange 13 on the side of the stem opposite to the rod 36 and that the edge of the lug 23^a is separated from the bore in the flange 13 by a slight clearance. It will be noted that the external diameter of the float 30 is slightly smaller than the internal diameter of the cap 31. As a result of this construction and 80 relation of the parts, when the handle 38 is operated to move the rod 36 into engagement with the stem 23, the first action that occurs is to move the lower end of the stem to the right, thus tilting the valve and float mechanism and lifting one edge of the valve member 22 sufficiently to break the seal effected by the valve member. This action continues until the lug 23^a engages the bore in the flange 13 and the upper surface of the float on the opposite side engages the inside of the cap 31, at which time the downward pressure on the valve member 22 is materially reduced, and continued motion of the handle 38 slides the inclined surface 36^b under the lower end of the stem 23 and lifts said stem, the valve member 22 and the float 30 bodily away from the valve seat 15, which action continues until the upper portion of the valve member 22 enters the opening 17^c. 85 This removes the valve member from the path of the water rushing through the casing and permits the float to hold the valve member in its uppermost position in the opening 17^c, at which time the top of the float engages the inner surface of the cover 31 to prevent further upward movement of the float and parts carried thereby.
- 90 It will be observed that during the closed condition of the valve the discharge ends of 95

100 105 110 115 120 125 130

130

the holes 25 are not in communication with the inlet connection 11 and that therefore any water that may have been in the float drains therefrom through the bore 26 and 5 the holes 25, this draining action being permitted by flow of air into the float through the tube 24. At the same time, however, the apertures 19, 19^a permit water from the inlet connection 11 to enter the lower part of 10 the float receptacle around the outside of the float until a condition of equilibrium is established between the air compressed in the upper part of the float chamber and the pressure exerted on the water. The float 15 therefore at this time, is in a condition for securing a maximum of floating effect which is exerted in the manner above described as soon as the valve member 22 is raised sufficiently to enter the lower end of the opening 20 17^c.

When the float is in its uppermost position as above described, due to the operation of the valve, the holes 25 are in communication at their outer ends with water under 25 pressure flowing to and through the valve seat 15. As a result, water gradually enters the float through the holes 25 and the clearance 26, at a rate determined by the cross section of the upper end of the air tube 24. As the air escapes from the float through the tube 24, the level of the water rises in the float until the buoyant effect of the float is reduced to a point such that it is no longer able to support the valve mechanism in its upper position and the valve member 22 then begins to descend from the 30 opening 17^c. This action continues until the upper surface of the valve member is below the opening 17^c, at which time the water moving rapidly through the valve seat 15 acts upon the upper surface of the valve member to move it positively against the valve seat 15 thus ending the flushing operation. The parts are at that time again 35 in the position indicated in Fig. 1, for which position as above described, the water is free to flow from the float into the outlet connection 12, thus placing the valve mechanism in condition for another operation. 40 If for any reason it is desirable to secure a longer flushing interval than would result from the automatic operation above described, the handle 38 may be again actuated to positively hold the valve from its seat and flushing will continue as long as 45 the valve is so held, after which upon releasing the handle the valve will return to its closed position in the manner above described.

50 It will be understood that the operation of the flushing mechanism in the manner described secures automatically a certain interval of flushing even though the operating handle be but momentarily actuated, this 55 interval of flushing being determined by

the cross section of the air tube 24. It will also be observed that the washer 18 protects the upper surface of the valve member 22 from rush of water during the open condition of the valve and thus permits the 70 automatic timing of the flushing operation above described.

While I have shown my invention in the particular embodiment above described, it will be understood that I do not limit myself to this exact construction but that I may employ equivalents known to the art at the time of the filing of this application without departing from the scope of the 75 appended claims.

What I claim is:

1. In a flushing valve, the combination of a casing having water supply and outlet connections, a valve seat carried by said casing, a movable valve member for engaging said seat to interrupt communication between said connections, a float in said casing connected with said valve member, a receptacle in said casing for receiving said valve member and protecting it from the action of water flow through said casing, and devices for moving said valve member into said receptacle, said devices comprising a valve stem extending from said valve member, a rod having a beveled end for moving said stem, an operating member for moving said rod, said stem and said rod having line contact engaging surfaces, and lugs extending from said stem spanning said rod for retaining said engaging surfaces in line contact relation. 90

2. In a flushing valve, the combination of a casing having water supply and outlet connections, a valve seat carried by said casing, a movable valve member for engaging said seat to interrupt communication between said connections, a float in said casing connected with said valve member, and devices for moving said valve member from its seat, said devices comprising a valve stem extending from said valve member, a rod having a beveled end for moving said stem, an operating member for moving said rod, said stem and said rod having line contact engaging surfaces, and lugs extending from said stem spanning said rod for retaining said engaging surfaces in line contact relation. 105

3. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, and devices for moving 110

- 5 said valve member into said receptacle, said receptacle comprising a partition extending across said casing and having an opening therethrough forming the side wall of said 70
 5 receptacle, and a disc around said valve stem resting on said partition forming the top of said receptacle.
- 6 4. In a flushing valve, the combination of a casing having water supply and outlet 75
 10 connections, a valve seat carried by said casing, a movable valve member for engaging said seat to interrupt communication between said connections and having a stem of smaller diameter extending upwardly 80
 15 therefrom, a float in said casing connected with said valve stem, a receptacle in said casing for receiving said valve member and protecting it from the action of water flow through said casing, and devices for moving 85
 20 said valve member into said receptacle, said receptacle comprising a partition extending across said casing and having an opening therethrough forming the side wall of said 90
 25 receptacle, and a disc around said valve stem resting on said partition forming the top of said receptacle, said partition having a recess therein loosely containing said disc.
- 30 5. In a flushing valve, the combination of a casing having water supply and outlet 95
 35 connections, a valve seat carried by said casing, a movable valve member for engaging said seat to interrupt communication between said connections and having a stem of smaller diameter extending upwardly 100
 40 therefrom, a float in said casing connected with said valve stem, a receptacle in said casing for receiving said valve member and protecting it from the action of water flow through said casing, and devices for moving 105
 45 said valve member into said receptacle, said receptacle comprising a partition extending across said casing and having an opening therethrough forming the side wall of said 110
 50 receptacle, and a disc around said valve stem resting on said partition forming the top of said receptacle, said partition being screwed into said casing and the said opening through said partition being flat sided to facilitate turning said partition in said 115
 55 casing.
- 60 6. In a flushing valve, the combination of a casing having water supply and outlet 120
 65 connections, a valve seat carried by said casing, a movable valve member for engaging said seat to interrupt communication between said connections and having a stem of smaller diameter extending upwardly 125
 70 therefrom, a float in said casing connected with said valve stem, a receptacle in said casing for receiving said valve member and protecting it from the action of water flow through said casing, and devices for moving 130
 75 said valve member into said receptacle, said receptacle comprising a partition extending across said casing and having an opening

- of smaller diameter extending upwardly therefrom, a float in said casing connected with said valve stem, a receptacle in said casing for receiving said valve member and 5 protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall 10 of a float compartment, and said partition having a second opening therethrough permitting water to enter said float compartment.
10. In a flushing valve, the combination of a casing having water supply and outlet connections, a valve seat carried by said casing, a movable valve member for engaging said seat to interrupt communication between said connections and having a stem 15 of smaller diameter extending upwardly therefrom, a float in said casing connected with said valve stem, a receptacle in said casing for receiving said valve member and protecting it from the action of water flow 20 through said casing and having a clearance opening through its top wall for said stem and devices for moving said valve member into said receptacle, said float and valve member having a water passageway there- 25 through extending from within said float to the opposite side of said valve member within its seat engaging portion.
11. In a flushing valve, the combination of a casing having water supply and outlet connections, a valve seat carried by said casing, a movable valve member for engaging said seat to interrupt communication between said connections and having a stem 30 of smaller diameter extending upwardly therefrom, a float in said casing connected with said valve stem, a receptacle in said casing for receiving said valve member and protecting it from the action of water flow 35 through said casing and having a clearance opening through its top wall for said stem, devices for moving said valve member into said receptacle, and an air passageway extending from the upper portion of the interior of said float to below said valve member.
12. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing 40 for receiving said valve member and protecting it from the action of water flow through said casing, devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall 45 of a float compartment, and said partition having a second opening therethrough permitting water to enter said float compartment.
13. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow 50 through said casing, devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall 55 of a float compartment, and said partition having a second opening therethrough permitting water to enter said float compartment.
14. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow 60 through said casing, devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall 65 of a float compartment, and said partition having a second opening therethrough.

through permitting water to enter said float compartment, and a cover for said casing forming the upper portion of said float compartment.

- 5 15. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and 10 protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, 15 said partition being screwed into said casing and the said opening through said partition being flat sided to facilitate turning said partition in said casing, said partition having a recess therein loosely containing said disk, said float and valve member having a water passageway therethrough extending from within said float to the opposite side of said valve member within its seat engaging portion. 20
- 15 16. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, devices for moving said valve member into said receptacle, said receptacle comprising a partition extending across said casing and having an opening therethrough forming the side wall of said receptacle, and a disc around said valve stem resting on said partition forming the top of said receptacle, 25 said partition being screwed into said casing and the said opening through said partition being flat sided to facilitate turning said partition in said casing, said partition having a recess therein loosely containing said disk, said float and valve member having a water passageway therethrough extending from within said float to the opposite side of said valve member within its seat engaging portion. 30
- 20 17. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, 35 said partition being screwed into said casing and the said opening through said partition being flat sided to facilitate turning said partition in said casing, said partition having a recess therein loosely containing said disk, said float and valve member having a water passageway therethrough extending from within said float to the opposite side of said valve member within its seat engaging portion, and an air passageway extending from the upper portion of the interior of said float to below said valve member. 40
- 25 18. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, 45 said partition being screwed into said casing and the said opening through said partition being flat sided to facilitate turning said partition in said casing, said partition having a recess therein loosely containing said disk, said float and valve member having a water passageway therethrough extending from within said float to the opposite side of said valve member within its seat engaging portion, and an air passageway extending from the upper portion of the interior of said float to below said valve member. 50
- 30 19. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, said partition being cup-shaped to form a 55
- 35 120
- 40 125
- 45 130

float compartment and screwed into said casing and the said opening through said partition being flat sided to facilitate turning said partition in said casing, said partition having a second opening therethrough permitting water to enter said float compartment, said float and valve member having a water passageway therethrough extending from within said float to the opposite side of said valve member within its seat engaging portion.

20. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, devices for moving said valve member into said receptacle, said receptacle comprising a partition extending across said casing and having an opening therethrough forming the side wall of said receptacle, and a disc around said valve stem resting on said partition forming the top of said receptacle, said partition being cup-shaped to form a float compartment and screwed into said casing and the said opening through said partition being flat sided to facilitate turning said partition in said casing, said partition having a second opening therethrough permitting water to enter said float compartment, said float and valve member having a water passageway therethrough extending from within said float to the opposite side of said valve member within its seat engaging portion, and an air passageway extending from the upper portion of the interior of said float to below said valve member.

21. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, and devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall of a float compartment, and said partition having a second

opening therethrough permitting water to enter said float compartment, said float and valve member having a water passageway therethrough extending from within said float to the opposite side of said valve member within its seat engaging portion.

22. In a flushing valve, the combination of a casing having water supply and outlet connections, a valve seat carried by said casing, a movable valve member for engaging said seat to interrupt communication between said connections and having a stem of smaller diameter extending upwardly therefrom, a float in said casing connected with said valve stem, a receptacle in said casing for receiving said valve member and protecting it from the action of water flow through said casing, devices for moving said valve member into said receptacle, said receptacle comprising a partition extending across said casing and having an opening therethrough forming the side wall of said receptacle, and a disc around said valve stem resting on said partition forming the top of said receptacle, said partition and said disc forming the bottom wall of a float compartment, and said partition having a second opening therethrough permitting water to enter said float compartment, said float and valve member having a water passageway therethrough extending from within said float to the opposite side of said valve member within its seat engaging portion, and an air passageway extending from the upper portion of the interior of said float to below said valve member.

23. In a flushing valve, the combination of a casing having water inlet and outlet connections, a valve seat in said casing between said connections comprising a ring of yielding material, a valve disc for engaging said seat, a stem extending from said valve disc loosely through said seat, a partition crossing said casing above said valve disc and provided with a central aperture, a central extension projecting upwardly from said valve disc loosely through said partition aperture, a float secured to the upper end of said extension and loosely contained in said casing, and devices for moving said valve disc upwardly from said valve seat, said devices comprising a rod reciprocable through the side wall of said outlet connection and having an inclined face adjacent the lower end of said stem for raising the latter, a spring tending to hold said rod in its outermost position, a flange projecting outwardly from the outer end of said rod, an operating member having a flanged spherically conformed end for engaging said rod flange, an operating handle projecting from said operating member, the lower end of said stem being conformed to engage said inclined face with line contact, and lugs ex-

tending from said stem for maintaining said rod and said stem in line contact engaging relation.

24. In a flushing valve, the combination 5 of a casing having water inlet and outlet connections, a valve seat in said casing between said connections comprising a ring of yielding material, a valve disc for engaging said seat, a stem extending from said valve 10 disc loosely through said seat, a partition crossing said casing above said valve disc and provided with a central aperture, a central extension of smaller diameter projecting upwardly from said valve disc loosely 15 through said partition aperture, a float secured to the upper end of said extension and loosely contained in said casing, and devices for moving said valve disc upwardly from said valve seat, said partition having 20 an opening therein for containing said valve disc in its raised position.

25. In a flushing valve, the combination 25 of a casing having water inlet and outlet connections, a valve seat in said casing between said connections comprising a ring of yielding material, a valve disc for engaging said seat, a stem extending from said valve disc loosely through said seat, a partition crossing said casing above said valve disc 30 and provided with a central aperture, a central extension of smaller diameter projecting upwardly from said valve disc loosely through said partition aperture, a float secured to the upper end of said extension 35 and loosely contained in said casing, devices for moving said valve disc upwardly from said valve seat, said partition having an opening therein for containing said valve disc in its raised position, said partition having 40 a recess in its upper surface surrounding said opening, and a washer loosely contained in said recess to close the upper end of said opening and containing said partition aperture.

45. 26. In a flushing valve, the combination 50 of a casing having water inlet and outlet connections, a valve seat in said casing between said connections comprising a ring of yielding material, a valve disc for engaging said seat, a stem extending from said valve disc loosely through said seat, a partition crossing said casing above said valve disc and provided with a central aperture, a central extension projecting upwardly from 55 said valve disc loosely through said partition aperture, a float secured to the upper

end of said extension and loosely contained in said casing, devices for moving said valve disc upwardly from said valve seat, said devices comprising a rod reciprocable 60 through the side wall of said outlet connection and having an inclined face adjacent the lower end of said stem for raising the latter, a spring tending to hold said rod in its outermost position, a flange projecting outwardly from the outer end of said rod, an operating member having a flanged spherically conformed end for engaging said rod flange, and an operating handle projecting from said operating member, a flange 65 projecting inwardly to support said valve seat, and a lug on the side of said stem opposite said rod to engage said last named flange to limit tilting movement imparted to said stem by said rod. 75

27. In a flushing valve, the combination 80 of a casing having water inlet and outlet connections, a valve seat in said casing between said connections comprising a ring of yielding material, a valve disc for engaging said seat, a stem extending from said valve disc loosely through said seat, a partition crossing said casing above said valve disc and provided with a central aperture, a central extension projecting upwardly from 85 said valve disc loosely through said partition aperture, a float secured to the upper end of said extension and loosely contained in said casing, devices for moving said valve disc upwardly from said valve seat, said devices comprising a rod reciprocable through the side wall of said outlet connection and having an inclined face adjacent the lower end of said stem for raising the latter, a spring tending to hold said rod in its outermost position, a flange projecting outwardly from the outer end of said rod, an operating member having a flanged spherically conformed end for engaging said rod flange, and an operating handle projecting from 90 said operating member, a flange projecting inwardly to support said valve seat, and a lug on the side of said stem opposite said rod to engage said last named flange to limit tilting movement imparted to said stem by said rod, said float being a clearance fit in said casing to further limit said tilting movement. 100

In witness whereof, I hereunto subscribe my name this 26th day of September, A. D. 105 1923.

ALBERT S. HOFFMAN.
